(57) **CLAIM**

The ornamental design for a virtual reality device, as shown and described.

DESCRIPTION

FIG. 1 is a perspective view of a virtual reality device showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is an exploded perspective view thereof;

FIG. 8 is a perspective view thereof showing the state that the cover part (the upper part) of the subject design has been attached to the main part as being upside down;

FIG. 9 is a front view of FIG. 8;

FIG. 10 is a rear view of FIG. 8;

FIG. 11 is a left side view of FIG. 8;

FIG. 12 is a right side view of FIG. 8;

FIG. 13 is a top plan view of FIG. 8; and,

FIG. 14 is an exploded perspective view of FIG. 8.

The broken lines depict portions of the virtual reality device that form no part of the claimed design.

1 Claim, 13 Drawing Sheets
